CLAIM

The ornamental design for a protective cover for a razor cartridge, as shown and described.

DESCRIPTION

FIG. 1 is a front perspective of a protective cover for a razor cartridge;

FIG. 2 is front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear perspective view thereof.

The broken lines are shown for illustrative purposes only and form no part of the claimed design.
